UNITED STATES PATENT OFFICE.

HUGH HUMPHREYS, OF GRAND RAPIDS, MICHIGAN, ASSIGNOR TO OLIVER MACHINERY COMPANY, OF GRAND RAPIDS, MICHIGAN, A CORPORATION OF MICHIGAN.

TOOL REST.

Application filed August 11, 1924. Serial No. 731,332.

This invention relates to a novel construction of tool rest such as is used with wood turning lathes. The work turned, in wood turning lathes, may be of different sizes and 5 diameters requiring that the tool rest on which the various turning tools such as chisels and the like bear be changed and adjusted for the sizes of the work. Also the work in its later stages is of smaller diameter than 10 the stock from which the finished article is made, this at times requiring frequent adjustment of the tool rest; while different positions of the rest relative to the length of the work are often required particularly 15 where the work is of greater length than the length of the tool rest. It is a primary object and purpose of the present invention to construct a very simple, practical and novel tool rest which may be adjusted either 20 lengthwise of the lathe bed or transversely thereof to many different positions. It is a further object and purpose of the invention to provide a novel construction of tool rest wherein the control for releasing the rest for 25 movement and for tightening it against movement when it has been placed at a desired position, is located in front of the lathe and at a point most directly accessible to the operator of said lathe, this aiding in accomplishing speed of adjustment of the tool rest 30 to various positions. A still further object of the invention is to construct the tool rest in such manner that a blue print holder may be adjustably applied thereto in position such 35 that a blue print held by said holder is also located directly in front of the lathe operator, moves with the tool rest and is capable of adjustment with respect to the tool rest in a direction transverse to the length of the 40 lathe whereby the blue print may be kept out of the way of the rapidly rotating work held between the head and tail stock spindles of the lathe. Various other objects and purposes than those specifically stated, all tending 45 to a particularly practical and efficient construction of the character stated will appear as understanding of the invention is had from the following description taken in connection with the accompanying drawings in 50 which,

Fig. 1 is a fragmentary enlarged vertical section taken transversely of the lathe bed and longitudinal of the tool rest which is mounted thereon.

Fig. 2 is a vertical section substantially on 55 the plane of line 2—2 of Fig. 1.

Fig. 3 is a fragmentary perspective view illustrating the tool rest with the print holder thereon attached to the lathe bed and showing the relation of the tool rest and 60 blue print holder to the work.

Fig. 4 is a horizontal section taken on the line 4—4 of Fig. 1.

Fig. 5 is an end elevation of the eccentrically mounted shaft forming one element of 65 the tool rest construction and

Fig. 6 is a fragmentary vertical section taken in one side and at the rear end of the tool rest support showing the attachment of 70 the blue print holder which is shown in elevation.

Like reference characters refer to like parts in the different figures of the drawings.

The lathe may be of any conventional construction including a bed 1 in the upper side 75 and lengthwise of which is a continuous slot 2. The tail stock 3 and the head stock 4 are mounted on the bed in the usual manner, the tail stock being capable of adjustment 80 lengthwise of the bed so as to receive the work 5 between its spindle and the usual face plate carried on the head stock spindle.

The tool rest support of this invention includes in its construction a front vertically positioned post 6 integral with which and extending to the rear are spaced apart horizontal bars 7 connected at their rear ends by an integral cross member 8, there being a longitudinal slot 9 between the bars 7 located between the post 6 and said rear cross member 8. This tool rest support is faced 85 on its under side so as to bear against the upper plane surfaces of the front and rear members of the bed 1, as shown, and the same is adapted to be moved lengthwise of 90 or transversely across the bed. The post 6 is bored downwardly from its upper end so that the tool rest proper may be mounted 95 therein, said rest consisting of an upper head 10 from which a depending rod 11 extends passing into the opening bored in the post 6 as best shown in Fig. 1. Any practical means for securing the rod 11 in any 100 position to which it may be vertically adjusted may be used and I have shown a rod 12 screw threaded at one end and equipped with head 12^a at its opposite end through

which a rod 13 may pass to serve as a handle to operate the screw, the post 6 at one side being recessed for the reception of a sleeve 14 which is located around the rod 12 and disposed between the head 12^a and the vertical rod 11 as shown in Fig. 4, whereby on operating the screw threaded rod 12 in one direction sleeve 14 binds against the rod 11 and secures it in position. It is obvious that the tool rest proper may be readily released and raised or lowered to a desired position and then secured in such position almost instantly.

A rod or shaft 15 is located between and parallel to the side bar 7 of the tool rest construction. At its rear end it is provided with a pintle 16 of reduced diameter, the axis of which is eccentrically located with respect to the axis of the shaft 15. This pintle 16 is rotatably mounted in a suitable bearing in the cross member 8. At its front end shaft 15 is also equipped with an eccentrically positioned pintle 17 of smaller diameter the axis of which is coincident with the axis of the pintle 16; and this front pintle 17 passes through and is rotatably mounted in a bearing sleeve 18 carried by the tool rest at its front end and at the lower end of the post 6. Handle 19 is pinned or otherwise suitably secured to the front end of the pintle 17 whereby the shaft may be rotated by manually operating the handle 19.

On the shaft 15 between its ends a head 20 is located, the shaft passing freely therethrough, and from said head 20 a rod 21 extends downwardly through the slot 2 and through a clamping block 22 located under the upper side of the lathe bed and formed so as to clamp against the upper side of the lathe bed at each side of the slot 2 as best shown in Fig. 1. The lower end of the rod 21 is threaded for the reception of nuts 23. It is evident that when shaft 15 is rotated so as to bring the same to its highest position, or nearly to its highest position, then if the nuts 23 are tightened so as to clamp the clamping block 22 securely against the upper side of the lathe bed the tool rest will be held securely in position against movement. The handle 19 is preferably secured to the part 17 so that when thus clamped said handle will extend downwardly at an angle to both the horizontal and vertical or it may approach a substantially vertical position. Then, whenever it is desired to release the tool rest all that is necessary is to grasp the handle 19 and turn it toward a horizontal position or even to and past horizontal position whereupon the shaft 15 is bodily lowered on account of its eccentric mounting, thus lowering the head 20 and rod 21 and the clamp 22 associated therewith so as to release the tool rest for movement either lengthwise of the lathe bed

or transversely thereof, the transverse movement being permitted by reason of the free sliding movement of the shaft 15 through the head 20. And after the tool rest has been moved to a desired position it can be instantly clamped in place by moving the handle 19 downwardly as far as it will go or until the clamping block 22 again binds securely against the under side of the upper part of the lathe bed due to the elevation of head 20. This is a particularly speedy manner of clamping and unclamping the tool rest and it will be noted that the handle 19 is in the most convenient place for access by the operator of the lathe, all of these features, together with the very simple construction of the tool rest support which is practically a single integral casing combining to make the invention one of great utility and merit.

At the rear end of the tool rest support a blue print holder is mounted, the same consisting of a vertical rod 24 which at its lower end is turned at right angles, making an arm 25 which passes into an opening made in the rear end of one of the bars 7 of the tool rest support, which bar is cored out, as indicated at 7^a, for a distance to permit adjustment of the part 25 in or out varying distances. When in a desired position the blue print holder is secured by a set screw 26 as shown in Fig. 6. The rod 24 extends upwardly and at its upper end is equipped with any preferred type of spring clip 27 for the holding of a blue print, as indicated at 28. If the work is of large size, the blue print holder may be moved farther back and for a smaller size it may be moved forward as is evident. The blue print holder moves with the tool rest and accordingly is always directly in front of the lathe operator making it particularly practical and efficient in this respect.

The invention is defined in the claims appended hereto and is to be considered as comprehensive of all forms of structure coming within their scope.

I claim:

1. In combination, a lathe including a lathe bed having a longitudinal slot in its upper side, a tool rest support located above and bearing against the upper side of the lathe bed, said support including spaced apart parallel bars connected at their ends, a shaft rotatably mounted on eccentrically located pintles at its ends and located between the said parallel bars, a handle at the front end of the shaft for turning the same, a head having an opening through which the shaft passes whereby the tool rest support and shaft may slide longitudinally of the shaft with reference to the head, a rod depending from the head and extending through the slot in the lathe bed, a clamping block located against the under side of the

upper side of the lathe bed, nuts threaded onto the depending rod below said clamp and a tool rest member carried by the tool rest support adjacent the front end thereof, substantially as and for the purposes described.

2. A tool rest support comprising a single casting having parallel spaced apart side bars, a cross member connecting the rear ends of the cross bars and a tool rest post at the front end of and integrally connected to and connecting said side bars at their front ends, a shaft located between and paralleling the side bars of the tool rest support, said shaft having alined eccentrically positioned pintles at its ends rotatably mounted in said cross member and the lower end of said post, a handle attached to one of said pintles for manual operation, a member having an opening through which the shaft passes whereby the tool rest support and shaft may slide longitudinally of the shaft with reference to the member, a rod depending from said member, a clamping block through which the rod passes and means for adjusting the clamping block on the rod, substantially as described.

3. In a device of the class described, an elongated tool rest support having a longi-

tudinal slot therein, an eccentrically mounted shaft located in said slot, a handle for manually turning the shaft, a head having an opening through which the shaft passes whereby the support and shaft may slide longitudinally of the shaft with reference to the head, a rod depending from the head, a clamping block through which the rod passes and means adjustably mounted on the end of the rod for adjusting the position of the clamping block, substantially as and for the purposes described.

4. In a device of the class described a tool rest support having an elongated body, a shaft extending longitudinally of said body adjacent thereto and eccentrically mounted on said body, means for manually turning the shaft, a head having an opening through which the shaft passes whereby the body and shaft may slide longitudinally of the shaft with reference to the head, a rod depending from the head, a clamping block through which the rod passes and means adjustably mounted on the end of the rod for adjusting the position of the clamping block.

In testimony whereof I affix my signature.

HUGH HUMPHREYS.
